DESIGN FOR A CALENDAR STAND

Boris Blecher, Philadelphia, Pa.

Application November 1, 1946, Serial No. 134,442

Term of patent 14 years

(Cl. D74—5)

To all whom it may concern:

Be it known that I, Boris Blecher, a citizen of the United States and a resident of Philadelphia, county of Philadelphia, State of Pennsylvania, have invented a new, original, and ornamental Design for a Calendar Stand, of which the following is a specification, reference being had to the accompanying drawings, forming a part thereof, wherein:

Figure 1 is a front perspective view of a calendar stand showing my new design in full lines, the broken line showing being for illustrative purposes only and being omitted from the other figures for convenience of illustration.

Figure 2 is a front elevational view thereof;
Figure 3 is a side elevational view thereof; and
Figure 4 is a top plan view thereof.

I claim:

The ornamental design for a calendar stand, as shown and described.

BORIS BLECHER.
